FASTENING-INSERTING MACHINE

George Goddu, Winchester, Mass., assignor to
United Shoe Machinery Corporation, Paterson,
N. J., a corporation of New Jersey

Original application May 3, 1930, Serial No.
449,457. Divided and this application January
2, 1932, Serial No. 584,396

4 Claims. (Cl. 1—20)

This invention relates to machines for inserting fastenings and is illustrated herein as embodied in a staple inserting machine. Goodyear welt shoes, as well as shoes of some other kinds, are made with an insole having a rib to which the shoe upper is secured during or after the lasting operation by staples driven through the shoe upper into the rib of the insole and clenched by an anvil bearing against the inner surface of the rib. In many instances the staples are inserted by a side lasting machine which is utilized to work the portion of the shoe upper extending between the heel breast line and the tip line into lasted relation to the last and insole. They are, therefore, the sole means relied upon to hold the upper in lasted position up to the time of the inseaming operation by which the welt is secured to the lasted upper and insole. It is therefore important that the upper be stapled to the rib in a manner which will insure that the rib cannot yield outwardly, thereby lessening the tension of the lasted upper and resulting in a poorly lasted shoe.

It is accordingly an object of the present invention to provide a machine which will insert and clinch staples in such a manner that not only will the staples be securely anchored in the insole, but the rib will also be prevented from yielding outwardly under the tension imposed by the lasted upper leather. As illustrated herein, this is performed by the use of a machine which clenches the entering ends of the legs of the staples against an anvil positioned in the angle between the inner surface of the rib and the outer surface of the insole and closely adjacent to the base of the rib, the anvil being provided with clinching cavities formed and arranged to clenche the entering ends of the legs of the staple in a substantially helical form, the helically clenched portions lying in the extreme base of the rib of the insole and in the substance of the insole adjacent to but below the rib. The strain exerted by the shoe upper on the staples is thus transmitted to the body of the insole in such a way that there is no danger of the rib yielding and allowing the shoe upper to become slack.

The fastening, article and method disclosed in this application are not claimed herein since they form the subject-matter of and are claimed in my copending application for United States Letters Patent Serial No. 449,457, filed May 3, 1930 of which this application is a division.

It should be understood that the invention is not limited to use in connection with machines for use in the staple lasting of shoes since ma-

chines constructed in accordance with the invention may be used for other purposes than the securing of shoe uppers in lasted relation and fastenings other than staples may be clenched by use of machines arranged in accordance with the invention.

In one of its aspects my invention comprises a machine for inserting fastenings having an anvil provided with a clinching surface or surfaces formed and arranged to cause the entering ends of the fastenings to curve in substantially helical paths. In another aspect, my invention comprises an anvil having clinching cavities formed to direct the legs of a staple progressively and uniformly away from each other and away from the plane of the bar of the staple whereby the two legs of the staple are clenched substantially in the form of right- and left-hand helixes respectively. With the above and other objects and features in view, the invention will now be described in connection with the accompanying drawing and pointed out in the claims.

In the drawing,

Fig. 1 is a side elevation of a fragment of a side lasting machine provided with means for inserting staples to secure a shoe upper in lasted relation to an insole and last, the shoe upper, the insole and the last being shown in cross section;

Fig. 2 is a view on a somewhat larger scale of the work engaging portions of the machine of Fig. 1 and of the work piece which they engage, showing particularly the form and the location in which the staple is clenched;

Fig. 3 is a diagrammatic perspective view on a still larger scale showing the driver and clinching anvil of the machine together with a staple substantially at the conclusion of the clinching operation;

Fig. 4 is a view on yet a larger scale of the clinching anvil of the machine, a partly clenched staple being indicated at the left-hand side of that figure;

Figs. 5 and 6 are longitudinal sectional views through the clinching anvil on the lines V—V of Fig. 4, showing the relation of the anvil to a staple at different points in the clinching operation;

Fig. 7 is a section on the line VII—VII of Figs. 4 and 6; and

Fig. 8 is a section on the line VIII—VIII of Figs. 4 and 6.

As pointed out above, the invention is disclosed for use in the staple lasting of shoes since ma-

chines constructed in accordance with the invention may be used for other purposes than the securing of a shoe upper in lasted relation and fastenings other than staples may be clenched by use of machines arranged in accordance with the invention.

As pointed out above, the invention is disclosed with reference to the securing of a shoe upper in lasted relation to an insole and last, the shoe upper, the insole and the last being shown in cross section;

Fig. 2 is a view on a somewhat larger scale of the work engaging portions of the machine of Fig. 1 and of the work piece which they engage, showing particularly the form and the location in which the staple is clenched;

Fig. 3 is a diagrammatic perspective view on a still larger scale showing the driver and clinching anvil of the machine together with a staple substantially at the conclusion of the clinching operation;

Fig. 4 is a view on yet a larger scale of the clinching anvil of the machine, a partly clenched staple being indicated at the left-hand side of that figure;

Figs. 5 and 6 are longitudinal sectional views through the clinching anvil on the lines V—V of Fig. 4, showing the relation of the anvil to a staple at different points in the clinching operation;

Fig. 7 is a section on the line VII—VII of Figs. 4 and 6; and

Fig. 8 is a section on the line VIII—VIII of Figs. 4 and 6.

As pointed out above, the invention is disclosed for use in the staple lasting of shoes since ma-

upper in lasted relation to an insole and last by staples inserted through the shoe upper into the insole and clenched substantially in the form of a helix. Thus Figs. 1 and 2 show the nozzle 10, 5 driver 12 and anvil 14 of a staple side lasting machine which may be of the character fully disclosed in United States Letters Patent No. 1,796,451, granted March 17, 1931, upon an application filed in my name, to which reference 10 may be had for a complete disclosure of the machine. It will be understood that during the performance of the lasting operation the shoe upper 18 is worked progressively into lasted relation to the last 20 and insole 22, being secured 15 in that relation by staples 24 inserted through the marginal portion 16 of the upper 18 into the rib 26 of the insole 22, the entering ends of the legs of the staples 24 emerging from the inner surface of the rib 26 and being turned back into the substance of the rib and clenched by 20 clenching cavities 28 formed in the anvil 14. Conveniently the anvil 14 is adjustably mounted as indicated at 29 in Fig. 1.

In accordance with the present invention the 25 legs of the staples are clenched by the clenching cavities 28 of the anvil 14 in a substantially helical form, as indicated in Figs. 2, 3, 4 and 6, the clenched portion of the staple, moreover, being located in the rib 26 at its extreme base 30 and in the body of the insole adjacent to the rib, as best shown in Fig. 2. To accomplish this the portion of the anvil 14 containing the clenching cavities 28 is positioned against the base of the rib as illustrated in Figs. 1 and 2. The formation of the clenching surface of the cavities 28 35 is a three-dimensional curve, that is to say it is a curved surface every cross section of which is a curved line, and it is located out of the line of drive or non-symmetrically with respect to the line of drive as will be evident by a comparison of Figs. 4, 6, 7 and 8. The transverse curvature of the clenching cavities, that is, the curvature to successive sections parallel to lines VII—VII, 40 VIII—VIII of Fig. 4, increases progressively from the transverse median line toward the end of the anvil, and the longitudinal curvature of the clenching cavities increases progressively from the transverse median line of the anvil toward 45 its end, as best shown in Fig. 5. In other words, the radius of curvature of the clenching cavities decreases progressively away from the transverse median line of the anvil. The deepest portion 50 of any transverse curve falls adjacent to the line V—V of Fig. 4 which is parallel to the general plane of the driver 12. Referring particularly to Fig. 4, it will be noted that the line of drive (represented by a fragment of the cross bar of the staple indicated at 30 and the cross section of a leg of the staple indicated at 32) is substantially above and parallel to the line V—V 55 with respect to which portions of the clenching cavities adjacent to the line V—V are symmetrical. By reference to Figs. 5 and 6, and to Figs. 7 and 8, which are cross sections on the lines VII—VII and VIII—VIII respectively of Figs. 4 and 6, it will be seen that the clenching cavities are of such a formation that they are struck by the entering ends of the legs of a staple at a point above the deepest part of the clenching cavities thus deflecting the entering ends of the legs of the staple progressively away from each other symmetrically with respect to the median plane of the staple and at the same time downwardly (as viewed in Fig. 4) and ultimately back in the general direction from which they have 60

come, as indicated in Figs. 5 and 6, the result being a substantially helical or corkscrew clench as shown in Figs. 2 and 3 and as indicated by comparison of Figs. 4 and 6.

In order to facilitate the positioning of the 80 anvil 14 at the base of the rib 16, the lower portion of the anvil is cut off as indicated by the line 40 in Fig. 4. The portions of the clenching surfaces of the cavities 28 which are thus removed are non-essential and the clenching operation is in 85 no way interfered with by the elimination of this portion of the anvil.

When staples inserted to hold the upper in lasted relation to the insole and last of a Good-year welt shoe are clenched in this fashion the 90 entering ends of the staple legs are engaged when they emerge from the inner surface of the rib of the staple by the clenching cavities 28 of the anvil 14 and are curved progressively through a substantially helical path back into the rib 16 95 of the insole 22 and toward the inner surface of the insole, finally anchoring themselves in the insole in a manner which prevents the rib from yielding under the tension of the lasted shoe upper.

Having thus described my invention what I 100 claim as new and desire to secure by Letters Patent of the United States is:

1. A fastening inserting machine having a 105 clenching anvil and means for inserting a fastening through a workpiece presented to the machine and clenching its entering end against the anvil, a cavity in the anvil having a concave 110 clenching surface constructed and arranged to be struck by the end of a fastening at a point near the median line of the anvil, said surface increasing progressively in curvature both transversely and longitudinally of the clenching cavity toward the edge of the anvil and having the deepest part of the curve of said surface located 115 out of the line of drive to cause the entering end of the fastening to be deflected toward the deepest part of said curved surface and toward the edge of said anvil in a three-dimensional curve, thereby clenching the entering end of the fasten- 120 ing substantially in the form of a helix.

2. A staple inserting machine having a driver, a clenching anvil having clenching cavities, and means for causing relative movement of the driver and the anvil to insert staples into a work-piece and to clamp the entering ends of the legs of the staples after they have passed through the work-piece, the clenching cavities of the anvil being located relatively to the path of movement of the driver to cause the entering ends of the 130 staples to strike the cavities near the median line of the anvil, the curvature of the cavities increasing both transversely and longitudinally toward the edges of the anvil and the deepest part of the cavities being located out of the line of drive 135 and adjacent to the lateral edges of the anvil to cause the entering ends of the legs of the staples to curve in substantially helical paths.

3. A staple clenching anvil having clenching cavities arranged to clamp the entering ends of 140 the legs of a staple and formed and arranged symmetrically with respect to the median plane of the staple, the clenching cavities being formed with surfaces having successive transverse sections increasing in curvature and having the 145 longitudinal curvature of the cavities increasing from the transverse median line of the anvil toward the ends of the anvil with the deepest part of the curve of any transverse section located out of the general plane of the staple to 150

permit the legs of the staple to strike the surfaces at a point above the deepest part of the cavities to direct the legs of the staple progressively and uniformly away from each other and away from the plane of the bar and the legs of the staple in the earlier stages of the clenching operation whereby the two legs of the staple are clenched substantially in the form of right- and left-handed helixes respectively.

10 4. A staple clenching anvil having clenching cavities arranged to clench the entering ends of a staple and formed and arranged symmetrically with respect to the median plane of the staple,

the clenching cavities being formed to direct the legs of the staple progressively and uniformly away from each other and away from the plane of the bar and the legs of the staple in the earlier stages of the clenching operation and later toward each other but still away from the plane of the bar and the legs of the staple whereby the two legs of the staple are clenched substantially in the form of right- and left-handed helixes respectively each of substantially more than 180 degrees.
